TRAIN CONTROL SYSTEM

Filed Aug. 12, 1926

UNITED STATES PATENT OFFICE

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

TRAIN-CONTROL SYSTEM

Application filed August 12, 1926. Serial No. 128,894.

This invention relates to a train control system, and more particularly to an induction type of train control system; and has special reference to the provision of an improved induction train control system of the manual-automatic type.

A principal object of my present invention comprehends the provision of a vehicle carried apparatus for an induction train control system embodying automatic means operated in accordance with roadside conditions for producing a tripping operation of the vehicle carried apparatus to bring the vehicle to a halt combined with manually operable means for setting said vehicle carried apparatus to permit the same to move under a restricted speed.

A further prime object of my present invention comprehends the provision of vehicle carried apparatus for an induction train control system in which manual means are provided adapted to be operated by the engineman for resetting the vehicle carried apparatus to its normal unrestricted running condition provided the vehicle or train is running at or below the safe or restricted speed imposed by the manual setting mechanism.

A still further principal object of the invention comprehends the provision of a manual-automatic train control system of the nature referred to in which the manually operated restoring or resetting mechanism is adapted to be controlled by the cooperative efforts of the engineman and fireman acting simultaneously providing a maximum degree of safety in restoring the tripped vehicle carried apparatus to its normal running condition when the roadside conditions have cleared.

Still further prime objects of the invention reside and center about the provision of a system of the induction type in which the inductive tripping apparatus for the system is made to control all of the vehicle carried circuits including the manual setting and restoring mechanism, and the still further provision of a system in which the aforesaid manifold functions are carried out in a related way by means of instrumentalities and circuits composed of comparatively

few parts inter-related in an efficient operating manner.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiment of my invention, and in which:

The figure is a wiring diagrammatic view of the vehicle carried apparatus of the induction train control system embodying the principles of my present invention.

Referring now more in detail to the drawing, for controlling the movement of the train there is provided a valve magnet V having a construction such as disclosed in the patent to Allen B. Kendall No. 1,540,017, June 2, 1925, which valve is controlled by an electromagnet device M for opening the brake pipe of the air brake system to exhaust and for disconnecting the engineman's brake valve from the main reservoir when an automatic application of the brakes is effected. The electromagnet M is therefore the operated device and this electromagnet M is controlled automatically from the roadside and manually by the engineman or the combined efforts of the engineman and fireman on the vehicle to bring the vehicle to a halt, or to permit the same to move under a restricted speed and controlled by the speed of the train, and to permit the vehicle apparatus to be reset to unrestricted speed running conditions.

The electromagnet device M is normally under the control of a circuit closed at a contact 16 controlled by the operation of a control relay element CC, the circuit being energized from a transformer TR connected to the generator G, which generator may be of either the turbo or motor operated type, the said circuit comprising the secondary of transformer TR, conductors 12, 11 and 52, contact 16 normally closed, conductor 40, electromagnet M, and conductors 39 and 31, the secondary of the transformer being coupled to the primary which is connected

to the generator by means of the conductors 1, 6, 5 and 2. This normal electromagnet circuit therefore is normally closed with the relay element CC in normal or energized condition to permit unrestricted running of the vehicle as portrayed in the drawings.

The relay element CC comprises the armature of a relay having a field element C, and the relay is operated by controlling the energization of the armature CC in accordance with roadside conditions, the field C of said relay being always maintained energized from the transformer TR, the same being in a circuit comprising the transformer secondary, conductors 12 and 11, field element C and conductor 15. For controlling the armature relay element, there is provided a stick circuit controlled by another relay T-RT, which latter is in an inductor controlled circuit, the stick circuit for the relay element CC comprising the secondary of the transformer TR, conductors 12, 11 and 27, contact 14 of relay T-RT, conductor 26, the armature relay element CC, conductors 28 and 29, stick contact 17 of the control relay C, and conductors 30 and 31. Normally this circuit is closed as shown; and when this circuit is opened by the deenergization of the relay T-RT, the circuit will remain or persist in opened condition by the opening of the stick contact 17.

The relay T-RT is a trip relay having the field coil RT and the armature coil T, the former being energized from the transformer TR by the conductor connections 12, 11, 3, 4 and 15, while the armature element T is arranged in a circuit controlled by the tripping inductor TI, the latter comprising an energizing inductor *a* which is connected to the leads 1 and 2 of generator G and an energy receiving inductor *b* coupled to the energizing inductor *a*, the said energy receiving inductor being connected directly to the armature T of the trip relay by means of the conductors 9 and 10. The tripping inductor TI is adapted to cooperate with roadside apparatus, as is described and claimed in my copending application Ser. No. 506,595, filed October 10, 1921, for alternating current intermittent induction train control system, the same being also disclosed and claimed in my prior Patent No. 1,521,332 of Dec. 30, 1924.

Normally the receiving coil *b* of the tripping inductor TI is energized from the coil *a* so that the relay T-RT is energized to close its contacts and to maintain the same closed, closure of contact 14 maintaining the stick circuit to the control relay element CC energized for permitting the normal running conditions of the train. When, however, the tripping inductor TI moves over a roadside element (not shown) under "danger" or "caution" roadside conditions, the armature T of the trip relay T-RT is effectively deenergized so that its contacts are opened and the stick circuit to the control relay element CC

is opened for deenergizing the circuit to the magnet M. As soon as the tripping inductor TI has passed the cooperating roadside element, the trip relay T-RT is again energized to close its contacts, but under the assumed operation the stick circuit of the relay element CC remains open at the stick contact 17.

When a "danger" or "caution" operation is thus produced, it is desired to permit the engineman to restore the vehicle carried apparatus to a condition which will permit the vehicle to proceed under a speed restriction, such for example as under a speed of 15 or 20 miles per hour; and to accomplish this I provide a resetting or restoring circuit operable by the engineman, which circuit is made effective, however, only when the vehicle has first been reduced to the restricted speed, the said mechanism operating to restrain movement of the vehicle to or below said restricted speed and to again apply the brakes in case such speed is exceeded. This modifying mechanism comprises in the preferred construction a second control relay having the field C already described and an armature element DC, which armature element is under the control of a release switch RA connected in a manner to be described presently to be under the control of a speed circuit controller SCC which is connected to a part of the vehicle and is operated in accordance with the speed thereof in a manner well known to those skilled in the art.

For manually operating the control relay element DC there is provided a circuit energized from the transformer TR which comprises conductors 12, 11 and 49, contact 13 of trip relay T-RT, conductors 32 and 34, relay element DC, conductors 35 and 45, impulse contact 22 of the release switch mechanism RA (which embodies a construction similar to that described and claimed in my copending application Ser. No. 634,053 of Apr. 23, 1923, for circuit controlling means), conductors 44, 43 and 38, contacts 25 and 24 of the speed controller SCC and conductor 31. With this circuit it will be seen that when the speed of the vehicle is below a predetermined limit closing the contacts 24 and 25, the impulse operation of the contact 22 will close the circuit to energize the relay element DC, the contact 13 being normally in closed condition. This circuit is but momentarily closed at the impulse contact 22 provided the speed does not exceed the predetermined limit; and to maintain this circuit closed I provide a stick contact arranged in multiple with the impulse contact 22, said stick contact being contact 20 of relay element DC connected in multiple to the impulse contact 22 by means of conductors 37, 43 and 44 on one side and conductors 36 and 45 on the other side thereof.

When this circuit is closed and maintained closed by the holding contact 20, a new circuit is established at the contact 19 of the

control relay element DC which places the electromagnet M under the control of the speed of the train, this new circuit comprising the transformer TR, conductors 11 and 51, the said contact 19, conductor 40, electromagnet M, and conductors 39 and 31 back to the transformer. This circuit is under the control of the speed controller, since the contact 19 thereof is controlled by the relay element DC and the latter is energized only under the assumed condition that the speed control contacts 24 and 25 are closed. If, therefore, after a manual setting of the circuit to the control element DC, the speed of 15 the vehicle exceeds the restricted speed, the relay element DC will be deenergized, opening its contacts, and the electromagnet M will be deenergized to bring the vehicle to a halt. However, after the speed of the vehicle is again reduced to or below the predetermined limit, the release switch RA may again be operated by the engineman to re-energize the relay element DC.

For apprising the engineman of the correct time when the release switch RA should be operated, I provide a signalling circuit embodying a signal L, which circuit is closed when a manual setting of the apparatus is required (after a tripping operation), and 30 when the speed of the vehicle has been reduced, this circuit comprising the secondary of transformer TR, conductors 12 and 11, a contact 18 of the relay element CC closed when the latter is tripped or deenergized, 35 contact 21 closed, conductor 42, signal L, conductors 43 and 38, speed control contacts 24 and 25, and conductor 31 back to the transformer. When the relay element DC is energized by operation of the switch RA, this 40 circuit will be opened at the contact 21 so that the cessation of the signal will indicate to the engineman that the relay element desired to be operated has been energized.

It will therefore be seen from the last- 45 described construction that the control relay element DC may be set by a manual operation of the engineman to permit the vehicle to proceed under a restricted speed when the vehicle carried apparatus has been tripped or operated in response to a "danger" or 50 "caution" roadside condition. It is very desirable when the roadside conditions are "danger" or "caution" to trip the vehicle carried apparatus at every roadside control station if the roadside conditions continue at "caution" or "danger", even though the vehicle is moving under a restricted speed, this so as to obtain a maximum degree of safety in a manual-automatic system. I therefore 55 provide means for controlling the relay element DC from the circuits controlled by the tripping inductor TI so that the second control relay element DC will be deenergized when the tripping inductor TI is tripped. 60 Preferably also I provide an acknowledging

means operated by the engineman for forestalling this tripping operation of the element DC so that when the engineman is alert and the vehicle is moving at or below the restricted speed, the tripping operation which becomes unnecessary may be avoided. This I accomplish by providing the contact 13 aforesaid in the circuit of the relay element DC as already described, this contact being normally closed by the energization of the inductor b and being opened when a tripping operation is produced. For forestalling this tripping operation I provide a contact 23 preferably made part of the release switch RA, which contact is arranged in parallel to the trip relay contact 13 by means of the conductors 41 and 32 on one side and the conductors 11 and 49 on the other side thereof. Manual closure of the contact 23 while the trip relay contact 13 is opened will thus maintain the control relay element DC energized to prevent an operation of the brakes, provided of course the speed controller contacts 24 and 25 are maintained closed. The said forestalling circuit comprises the following 90 elements: TR, 11, 23, 41, 34, the element DC, 35, 45, 22, 44, 43, 38, 25-24 (closed) 31 and back to TR.

For restoring or resetting the vehicle carried apparatus after a tripping operation 95 thereof and when the roadside conditions have cleared, I provide a second manually operable mechanism effective when the train is not exceeding the restricted speed for resetting the inductor controlled circuit and the clear control relay C-CC. In the preferred construction this manually operable mechanism embodies a circuit open at two points and adapted to be closed by the concerted or cooperative action of both the engineman and the fireman, and preferably when the vehicle is not exceeding the restricted speed. By this means the vehicle carried 100 apparatus may be restored to its normal unrestricted running condition with a maximum 110 of safety, the same requiring the alertness of both the engineman and the fireman and the cooperative efforts of both, with the vehicle running at a safe rate of speed.

For accomplishing these results the manually operable mechanism comprises the fireman's release button FRB and the engineman's release button ERB both connected in a circuit controlling the "clear" relay element CC, the circuit being operable provided the 115 "danger" control relay element DC is in an energized state, the latter being the case when the vehicle is running at or below the restricted speed. This circuit comprises the secondary of transformer TR, conductors 12, 11 and 27, contact 14, conductor 26, the relay armature CC, conductors 28 and 46, button FRB, conductor 47, button ERB, conductors 48, 45 and 36, contact 20 (closed when the restricted speed is not exceeded provided DC 120

has already been energized) conductors 37, 38, speed controller contacts 25 and 24 and conductor 31 back to the transformer TR. The closing of the relay element CC by this 5 operation will restore the vehicle carried apparatus to its normal condition. Under normal conditions when the speed of the vehicle is unrestricted the "danger" control relay element DC will be deenergized, placing the 10 same in the condition of operation shown in the drawings. For obtaining greater efficiency from the generator G, I prefer to provide the power factor compensator PFC connected by the conductors 7 and 8 to the generator leads 1 and 2.

15 The use and operation of the train control system embodying the principles of my present invention will in the main be fully apparent from the above detailed description thereof. It will be further apparent that while I have shown and described my invention in its preferred form, many changes and modifications may be made in the structure disclosed without departing from the spirit 20 of the invention, defined in the following claims.

I claim:

1. In an induction train control system, 30 vehicle carried apparatus comprising a device for controlling the movement of the train, an inductor controlled circuit operable when tripped by cooperating roadside apparatus for operating said device to stop the train, manual means for modifying the stop operation of said device and for placing the same under the control of the speed of the train to permit the train to move under a speed restriction, and manually operable mechanism effective only when the train is not exceeding 35 said restricted speed for resetting said inductor controlled circuit to reset the said device to its normal unrestricted operation.

2. In an induction train control system, 45 vehicle carried apparatus comprising a device for controlling the movement of the train, an inductor controlled circuit operable when tripped by cooperating roadside apparatus for operating said device to stop the train, means manually operable by the engineman 50 for modifying the stop operation of said device and for placing the same under the control of the speed of the train to permit the train to move under a speed restriction, and mechanism manually operable by the engineman and the fireman cooperating together 55 and effective only when the train is not exceeding said restricted speed for resetting said inductor controlled circuit to reset the said device to its normal unrestricted operation.

60 3. In an induction train control system, vehicle carried apparatus comprising a device for controlling the movement of the train, an inductor controlled circuit operable when tripped by cooperating roadside apparatus

for operating said device to brake the train, manual means for modifying the said operation of said device and for placing the same under the control of the speed of the train to permit the train to move under a speed restriction, and manually operable mechanism effective only when the train is not exceeding 70 said restricted speed for resetting said inductor controlled circuit to reset the said device to its normal unrestricted operation. 75

4. In an induction train control system, vehicle carried apparatus comprising a device for controlling the movement of the train, an inductor controlled stick circuit operable when tripped by cooperating roadside apparatus for operating said device for producing a persisting train control operation thereof, means manually operable by the engineman for modifying the operation of said device and for placing the same under the control of the speed of the train to permit the train to move only under a speed restriction, and mechanism embodying a circuit open at two points and adapted to be closed by the cooperative efforts of the engineman and fireman 80 and effective only when the train is not exceeding 85 said restricted speed for resetting said inductor controlled circuit to reset the said device to its normal operation.

5. In an induction train control system, 90 vehicle carried apparatus comprising a device for controlling the movement of the train, a control relay for controlling the operation of said device, an inductor controlled circuit operable when tripped by cooperating 95 roadside apparatus for tripping the said control relay to produce a train controlling operation in said device, a second control relay for placing said device under the control of the speed of the train to permit the train to move under a speed restriction, manually operable means for setting the said second control relay, and manually operable mechanism effective only when the train is not exceeding 100 said restricted speed for resetting said first-mentioned control relay to reset the said device to its normal unrestricted operation. 105

6. In an induction train control system, vehicle carried apparatus comprising a device for controlling the movement of the train, a control relay for controlling the operation of said device, an inductor controlled circuit operable when tripped by cooperating roadside apparatus for tripping the said control relay to produce a train controlling operation in said device, a second control relay for placing said device under the control of the speed of the train to permit the train to move under a speed restriction, means operable by the engineman for setting the said second control relay, and mechanism operable by the engineman and fireman acting together and effective only when the train is not exceeding 115 the said restricted speed for resetting said first-mentioned control relay to reset the said 120 device to its normal unrestricted operation. 125

device to its normal unrestricted operation.

7. In an induction train control system, vehicle carried apparatus comprising a device for controlling the movement of the train, a control relay for controlling the operation of said device, an inductor controlled circuit operable when tripped by cooperating roadside apparatus for tripping the said control relay to produce a train controlling operation in said device, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said device to its normal unrestricted operation, and means for tripping the said second control relay when the said inductor controlled circuit is tripped.

8. In an induction train control system, vehicle carried apparatus comprising a device for controlling the movement of the train, a control relay for controlling the operation of said device, an inductor controlled circuit operable when tripped by cooperating roadside apparatus for operating the said control relay to produce a train controlling operation in said device, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said device to its normal unrestricted operation, means for tripping the said second control relay when the said inductor controlled circuit is tripped and manually operable means for inhibiting the tripping of said second control relay.

9. In an induction train control system, vehicle carried apparatus comprising a device for controlling the movement of the train, a control relay for controlling the operation of said device, an inductor controlled stick circuit operable when tripped by cooperating roadside apparatus for tripping the said control relay to produce a train stopping operation in said device, a speed controller, a second control relay for placing said device under the control of the speed controller to permit the train to move under a speed restriction, manually operable means for setting the said second control relay, and manually operable mechanism effective only when the train is not exceeding the said restricted speed for resetting said first-mentioned control relay to reset the said device to its normal unrestricted operation.

- 65 10. In an induction train control system,

vehicle carried apparatus comprising a device for controlling the movement of the train, a control relay for controlling the operation of said device, an inductor controlled circuit operable when tripped by cooperating roadside apparatus for tripping the said control relay to produce a train stopping operation in said device, a speed controller, a second control relay for placing said device under the control of the speed controller to permit the train to move under a speed restriction, manually operable means for setting the said second control relay, and manually operable mechanism embodying a circuit open at two spaced points and adapted to be closed by the cooperative action of the engineman and fireman and effective only when the train is not exceeding the said restricted speed for resetting said first-mentioned control relay to reset the said device to its normal unrestricted operation.

11. In an induction train control system, vehicle carried apparatus comprising a device for controlling the movement of the train, a control relay for controlling the operation of said device, a trip relay for the control relay, an inductor controlled circuit operable when tripped by cooperating roadside apparatus for tripping the said trip and control relays to produce a train controlling operation in said device, a second control relay for placing said device under the control of the speed of the train to permit the train to move under a speed restriction, manually operable means for setting the said second control relay, and manually operable mechanism effective only when the train is not exceeding the said restricted speed for resetting said first-mentioned control relay to reset the said device to its normal unrestricted operation.

12. In an induction train control system, vehicle carried apparatus comprising a device for controlling the movement of the train, a control relay for controlling the operation of said device, a trip relay for the control relay, an inductor controlled circuit operable when tripped by cooperating roadside apparatus for tripping the said trip and control relays to produce a train controlling operation in said device, the said trip relay being automatically reenergized after a tripping operation, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said device to its normal unrestricted operation, and means connecting the trip relay with said second control relay for tripping the latter when the said inductor controlled circuit is tripped.

13. In an induction train control system,

- vehicle carried apparatus comprising a device for controlling the movement of the train, a control relay for controlling the operation of said device, an inductor controlled circuit operable when tripped by cooperating roadside apparatus for tripping the said control relay to produce a train controlling operation in said device, a second control relay for controlling the operation of said device, manually operable means for governing the 5 operation of said second control relay, manually operable mechanism for controlling the operation of said first control relay and means connecting said inductor controlled circuit with said second control relay for tripping the latter when the said inductor controlled circuit is tripped.
14. In an induction train control system, vehicle carried apparatus comprising a device for controlling the movement of the train, a control relay for controlling the operation of said device, a trip relay for said control relay, an inductor controlled circuit operable when tripped by cooperating roadside 10 apparatus for tripping the said trip and control relays to produce a train controlling operation in said device, a second control relay for controlling the operation of said device, manually operable means for governing the 15 operation of said second control relay and means connecting said trip relay with said second control relay for tripping the latter when the said inductor controlled circuit is tripped.
15. In an induction train control system, vehicle carried apparatus comprising a device for controlling the movement of the train, a control relay for controlling the operation of said device, an inductor controlled 20 circuit operable when tripped by cooperating roadside apparatus for tripping the said control relay to produce a train controlling operation in said device, a second control relay for controlling the operation of said device, manually operable means for governing the 25 operation of said second control relay, means connecting said inductor controlled circuit with said second control relay for tripping the latter when the said inductor controlled circuit is tripped.
16. In an induction train control system, vehicle carried apparatus comprising a device for controlling the movement of the train, a control relay for controlling the operation of said device, an inductor controlled circuit operable when tripped by cooperating roadside apparatus for tripping the said control 30 relay to produce a train controlling operation in said device, a speed controller, a second control relay for controlling the operation of said device, manually operable means for governing the operation of said second control relay and for placing the same under 35 the control of said speed controller, and means connecting said inductor controlled circuit with said second control relay for tripping the latter when the said inductor controlled circuit is tripped.
